UNITED STATES PATENT OFFICE

2,609,920

PAPERBOARD PROTECTOR FOR
PAINT BRUSHESWilliam A. Ringler, Wayne, Pa., assignor to The
Gardner Board and Carton Co., Middletown,
Ohio, a corporation of Ohio

Application August 23, 1949, Serial No. 111,785

3 Claims. (Cl. 206—15.1)

1

My invention relates to a knock down or collapsible paperboard structure designed for the protection of the bristle portion of paint brushes or the like.

Objects of the invention are the provision of improved structures of this class which nevertheless are simple in form and economical to produce, the provision of structures capable of repeated reuse, and not liable to destruction through repeated opening and closure, and the provision of structures giving enhanced protection to the article of merchandise with which they are to be used.

It is an object of my invention also to provide a structure which, where desired, may be maintained in semi-erected condition in the absence of the article, facilitating the reinsertion of the article therein.

It is an object of the invention to provide a paint brush protector which is suitable not only for use as a protection to the paint brush during initial shipment, storage and the like, but which also may be employed, as has hitherto been suggested, in preserving the bristles and molding the shape of the bristle assembly of paint brushes which have been used and cleaned. It is an object of the invention to provide a tight package for the bristle portion of a paint brush, resistant to the infiltration of dirt and dust. It is an object of the invention to provide a paint brush protector which is simple in manipulation, and which has other valuable features hereinafter set forth.

These and other objects of the invention which will later be indicated, or which will be apparent to one skilled in the art upon reading these specifications, I accomplish by that construction and arrangement of parts of which I shall now describe an exemplary embodiment. Reference is made to the accompanying drawings wherein:

Figure 1 is a plan view of a cut and scored paperboard blank produced in accordance with my invention.

Figure 2 is a partial perspective view of the blank after an initial step of erection.

Figure 3 is a partial perspective view of the protector in one form of the erected condition, ready to receive a paint brush.

Figure 4 is a partial sectional view taken along the section line 4—4 of Figure 3.

Figure 5 is a perspective view of the erected structure containing a paint brush, but prior to closure.

Figure 6 is a perspective view with parts in section showing the closed protector containing the paint brush.

Referring first to Figure 1 in which solid lines indicate lines of cut, dot-dash lines indicate lines of score, and dashed lines indicate lines of weakening, I have shown a paperboard blank having a main panel 1 forming the front panel of the structure. To the sides of the main panel there are articulated triangular side wall panels 2 and

2

3, to the outer edges of which closure panels 5 and 6 are articulated. These closure panels may be made in various shapes, but are conveniently made substantially triangular as shown, and so proportioned that their outer corners will overlap in the erected structure.

To the upper end of the main panel 1 I articulate an end wall panel 7. This panel bears an inner end wall extension 8 having a flap 9. Diagonally scored webs 10 and 11 interconnect the ends of the side wall elements 2 and 3 respectively and the ends of the end wall element 7.

To the lower edge of the main panel 1 I articulate a second panel 12 of substantially the same size. This panel forms a rear protecting panel for the paint brush. It bears at its end a tuck flap 13.

Cuts forming incomplete ellipses are formed in the end wall 7 and its extension 8. The ellipses are completed by score lines as shown, and the configurations are oppositely directed as indicated to form a tab 14 or 15 in each of the elements 7 and 8, so positioned as to coincide when the inner end wall element is folded inside the end wall 7.

The lapping portions of the closure elements 5 and 6 are provided with the respective parts 16 and 17 of a snap fastener or its equivalent. The flap 13 on the end of the inner protecting panel 12 is provided with a cut out as at 18 which, in the erected condition of the protector, will coincide with the tabs 14 and 15. The structure illustrated in Figure 1 may be made by ordinary cutting and scoring press operations from suitable boxboard or paperboard, previously printed as may be desired. The board may be heavily sized or otherwise treated to render it moisture resistant, to prevent weakening when a previously used and washed brush is placed therein. It may also, if desired, be treated so as to be resistant to the solvents of paints and enamels with which the brush is to be used, or to solvents and solutions employed for cleaning brushes. Where the structure is made of very heavy paperboard or boxboard for added strength, certain of the score lines may advantageously be weakened by cutting or slitting or perforating, as for example the diagonal score lines 19 and 20 of the corner webs 10 and 11, and the score 21 by which the flap 9 is articulated to the end wall extension 8.

Figure 2 shows my structure with the side wall elements 2 and 3 erected at right angles to the main panel 1. In use, the end wall extension 8 will be folded over inwardly of the end wall element 7. When this is done, and when the tab elements 14 and 15 are depressed to the outer side of the end wall 7, the engagement of the tab 14 in the orifice left by the tab 15 will serve to maintain the end wall and end wall extensions in erected condition. This relationship will be evident from Figures 3 and 4. The depression of the tabs 14 and 15 outwardly will also provide an

opening 22 through which the handle 23 of a paint brush may be passed.

The protector may be assembled about a paint brush in various ways. For example, the inner end wall extension 8 may be folded over inside the end wall 7, and the tabs 14 and 15 passed through to the outside. Then the handle 23 of a paint brush of the size for which the protector is designed may be passed through the opening 22 left by the tabs 14 and 15, and the bristle portion of the paint brush laid against the main panel 1. This will result in erecting the end wall structure with respect to the main panel. The side walls 2 and 3 may then be erected, the webs 10 and 11 folding bellows-wise and lying in folded condition either at the top of the bristle portion of the brush, or alongside it. The panel 12 will be folded over against the opposite face of the bristle portion of the paint brush, with the flap 13 tucked down inside the end wall. The closure flaps 5 and 6 will be folded over on top of the panel 12, and snap fastener elements 16, 17 interengaged. This will result in a structure such as is illustrated in Figure 6.

In an alternative erecting procedure, the side wall elements 2 and 3 may first be brought upwardly at right angles to the main panel 1, after which the end wall element 7 is folded upwardly, accompanied by the bellows folding of the webs 10 and 11. Then the end wall extension 8 may be folded over inwardly so as to cover the folded webs 10 and 11. The passing of the tabs 14 and 15 through to the outside will serve to lock together the end wall 7 and the inner end wall extension 8, giving the erected structure which is illustrated in Figure 3. With the panel 12 coplanar with the main panel 1, the brush may be inserted as illustrated in Figure 5, and then the structure closed as hereinabove described. In the erected and closed structure the flap 9 lies inside of and parallel to the main panel 1.

It will be understood that the structure herein described not only serves as a protection for the paint brush during initial shipment, storage and the handling incident to merchandising, but also that the purchaser of the brush will retain the protector and will return to it a used brush which has been thoroughly cleaned. In this instance the protector not only prevents damage to the bristles, but molds the bristle assembly into a tapered shape suitable for preservation and for future use.

Modifications may be made in my invention without departing from the spirit of it. Having described my invention in an exemplary embodiment, what I claim as new and desire to secure by Letters Patent is:

1. A paperboard protector for paint brushes and the like which comprises a single, integral, foldable blank having a main panel adapted to overlie one face of a brush, triangular side panels articulated to the side edges of the main panel, closure flaps articulated to the side edges of said side panels and adapted to overlap in the closed position, an end wall panel articulated to an end of the main panel, diagonally scored closure webs interconnecting the ends of the side and end wall panels and adapted to fold bellows-wise inwardly when the side and end wall panels are erected with respect to said main panel, an extension articulated to the free edge of said end wall panel which, when folded inwardly provides an inner end wall overlying the inwardly folded corner webs, said end wall panel and its extension having tabs formed therein, said tabs

adapted to be folded to provide an opening through which may pass the handle of a paint brush, one of said tabs being adapted to lock said end wall panel and its extension in erected condition, and a supplementary panel articulated to the other end of said main panel and bearing a tuck flap at its free end, said supplementary panel being of substantially the same size as the main panel, said tuck flap having a cut-out portion responding to the openings in said end wall panel and its extension, said tuck flap adapted to overlie said inner end wall forming extension with the cut-out portion thereof coinciding with the openings in said end wall panel and its extension.

2. The structure claimed in claim 1 wherein the closure flaps articulated to the side panels are respectively provided with the parts of a separable fastener.

3. A one-piece paperboard protector for paint brushes which comprises a cut and scored blank having a rectangular main panel adapted to overlie one face of a paint brush, triangular side panels articulated to the side edges of said main panel and tapered inwardly from top to bottom, closure flaps articulated to the side edges of said triangular side panels and adapted to overlap each other in the closed position, an end wall panel articulated to the upper end of said main panel, diagonally scored corner webs interconnecting the ends of said triangular side panels and said end wall panel and adapted to fold inwardly bellowswise when the triangular side walls panel and the end wall panel are erected with respect to said main panel, an extension articulated to the free edge of said end wall panel, which, when infolded provides an inner end wall panel underlying the inwardly folded corner webs, said end wall panel and its extension having centrally disposed mating openings therein through which the handle of a paint brush enclosed in the protector will pass, locking means on said end wall extension for securing said extension in erected position whereby said corner webs may be locked between said end wall panel and said extension and thereby maintain said triangular side panels and said end wall panel in the erected condition, a second rectangular panel articulated to the lower end of said main panel of substantially the same size of said main panel and adapted to overlie the opposite face of a brush placed in the protector, a tuck flap on the free end of said second rectangular panel, said tuck flap having a cut-out portion responding to the openings formed in said end wall panel and its extension, said tuck flap adapted to underlie said end wall extension with the cut-out portion coinciding with said openings, said overlapping closure flaps adapted to overlie said second rectangular panel in the erected structure, said closure flaps being provided with the parts of a separable fastener.
